OTTO PETERMANN, OF GROTON, NEW YORK, ASSIGNOR TO CORONA TYPEWRITER COMPANY, INC., A CORPORATION OF NEW YORK.

TYPE-WRITING MACHINE.

1,189,171.

Specification of Letters Patent. Patented June 27, 1916.

Application filed March 16, 1915. Serial No. 14,649.

To all whom it may concern:

Be it known that I, OTTO PETERMANN, a citizen of the United States, and a resident of Groton, county of Tompkins, and State of New York, have invented certain new and useful Improvements in Type-Writing Machines, of which the following is a full, clear, and exact description.

This invention relates more particularly to the universal bar action of visible type-writing machines.

In typewriting machines, it is desirable that a light elastic touch be secured, and it is further desirable that the construction be such that as little noise by the operation of the keys be made as possible. Where the keys are operated and strike suddenly against the universal bar and the resistance of the mechanism operated thereby is suddenly thrown upon the keys or key-operated levers, the resistance offered is not only hard on the touch but the impact of the keys in striking suddenly against the universal bar requiring sudden movement of the different parts, produces considerable noise.

One of the principal objects of the present invention is to overcome the objections referred to and to provide a universal bar action in which a light and elastic touch is secured and in which the parts operated by the universal bar have an accelerated movement of such a character that the key-operated levers during a portion of their movement simply move the universal bar without any other part of the mechanism, and during the continued depression of the keys gradually increase the movement of such parts so that at the final part of the movement of any one of the key-operated levers, the greatest movement is given to the parts operated by the universal bar.

Another object of the invention is to provide a construction wherein the universal bar is normally held at a distance away from the key-operated levers and in which the levers only move the universal bar at the initial part of their engagement with said bar, thus the impact is easy and very little noise is made on that account.

Other objects of the invention are to provide means whereby the universal bar has its position determined by the position of the spacing lever or levers; and to provide means whereby the arc of movement of the

universal bar is such that the arc of movement of the connection between the universal bar and the other part of the universal bar mechanism operated by said bar, tends to move away from each other and at an increasing rate of speed so as to impart an accelerated movement to the escapement and ribbon vibrator operating rocking frame or element.

A further object of the invention is to provide a simple and efficient construction of universal bar action which may be readily made and assembled.

A still further object of the invention is to provide a universal bar action which is particularly adapted for foldable typewriting machines in which the platen carriage and keys are brought into close relation so as to make the machine compact for transportation or other purposes.

With these and other objects in view, the invention will be hereinafter more particularly described with reference to the accompanying drawings, which form a part of this specification, and will then be pointed out in the claims at the end of the description.

In the drawings, Figure 1 is a longitudinal section of one form of machine embodying my invention. Fig. 2 is a fragmentary perspective view of the principal parts of the universal bar action; and Fig. 3 is a sectional plan view with parts broken away, the section being taken through the posts which support the carriage for platen shift movement.

While the invention is shown as applied more particularly to a special form of folding typewriter in which the carriage is folded forward over the keys, it will be understood that the invention or parts thereof may be employed in connection with writing machines of various kinds.

The frame 10 has the sides 11 connected at the front end by a transverse bar 12 and at the rear by an integral transverse bar or plate 13. Held to the sides 11 are the fulcrum plates or members 14 and 15. These plates or members have openings 15^a through which pass the body of screws 15^b, the ends of which enter threaded openings in the ends of the fulcrum rods 16. The fulcrum rods 16 extend transversely of the machine and at their ends abut against the plates 14 and 15.

the latter being clamped between the ends of the rods 16 and sides 11 of the frame, though instead of this method of securing these parts together any other suitable means 5 may be employed. A plurality of key-operated levers 17 are pivotally held to the transverse fulcrum rods 16 and are arranged in groups or banks in the usual way, the banks of keys corresponding in number to the 10 transverse rods 16 and are so positioned that a substantially uniform touch is secured. Each key-lever has a fulcrum portion 18 to span one of the transverse rods 16 and below the fulcrum portion is the body 19. Each 15 key-lever body has an operating key 20 forming a part of a standard or universal keyboard and each lever has an inner portion 21 from which projects upwardly a part 22. To the part 22 is connected a link 23, the 20 latter being connected at its upper end to one of the type-bars 24. The type-bars are pivoted to a segment or to hangers and each has a plurality of characters, either two or three type, according to the shift movements, 25 and as each key-lever is depressed, its co-operating type-bar has the type thereon forced upwardly and rearwardly against a platen 25. The platen 25 is mounted upon a carriage 26 which is adapted to move along a bed 27. 30 The bed 27 is held to arms 28 which are pivoted, at 29, to other arms so that the carriage and bed may be folded forward over the keys or forward thereof to make the machine compact. The carriage has a rack 30 35 adapted to be engaged by dogs 31 and 32, the latter being mounted upon a carrier 33 so that when the said carrier is moved, the dogs will operate in such a way as to permit letter-spacing movement to be given to the 40 carriage, said carriage being normally held under tension of a spring drum 34. The arms 28 are held to vertically movable posts 35, Fig. 3, and these posts are connected by a transversely extending rod 36. An arm or 45 arms 37 are connected to the rod 36 and said arm or arms are held to a transversely extending rod or shaft 38 forming a part of the shift movement to adapt the posts 35 together with the carriage and platen to be 50 given shift movements. Except as to the fulcrum plates 14 and 15 and the mounting of the transverse fulcrum rods 16, the parts thus far described are old and such parts may be of the usual or of any preferred construction.

A universal bar frame 39 substantially U-shaped in plan so as to form a light structure has side arms 40 which are held to a transversely extending rod 41. The rod 41 60 forms pivoting means for the frame 39 and has its ends beyond the side arms 40 held in ears or lugs 41^a of the fulcrum plates 14 and 15. The arms 40 form integral extensions of the transversely arranged universal bar 65 42 which overlies the key-operated levers 17,

the bar 42 and arms 40 constituting the universal bar frame 39. The universal bar 42 is adapted to be engaged by a bendable tongue 43 of each key-lever and is normally held at a distance above said tongue in order 70 that each key may be depressed a certain distance before the tongue engages the universal bar 42 of the universal bar frame 39. The universal bar 42 normally rests against the inner end 44 of the space-bar lever 45. 75 The space-bar lever has a finger portion or key 46 to which it is connected at one end and at the other end of said key or bar 46 is connected an arm 47. The arm 47 and the lever 45 have fulcrum portions 48 so as to be 80 suspended from a transversely extending fulcrum rod 49, the latter being held to the sides of the machine frame by pivot screws 49^a as shown in Fig. 3. The space-bar lever 45 is held in its normal position by a spring 85 50 one end of which is secured to the lever 45 and the other end to a transversely extending bar 51, the ends of which are held in slots 52 in the downwardly and forwardly extending portions 53 of the fulcrum plates 90 or members 14 and 15, there being a spring 54 for each key-lever 17 one end of which is held to said key-lever and the other end to said transverse bar 51 tending normally to keep the key-levers in their normal position 95 as usual. The space-bar lever 45 normally rests upon the transverse rod 38 and has its inner end positioned to limit the pivotal downward movement of the universal bar frame 39, the bar 42 being normally held 100 against the inner end of the space-bar lever 45 by springs 55 one end of which are held to the universal bar and their other ends to pendent parts or arms 56 on the fulcrum members 14 and 15, there being a spring at 105 each side of the machine.

The universal bar frame 39 has its side arms 40 provided with upwardly extending lugs or projections 57. These lugs or projections are connected by detachable or 110 other links 58 of any suitable construction to the lower ends of levers 59. The levers 59 are pivoted to the rear posts or brackets 60 for the slides or posts 35 or otherwise and at their upper ends said levers are connected by a transversely extending rod 61. This rod 61 extends across the machine and passes through vertical slots 62 in the rocker frame 63. The rocker frame comprises two vertically extending arms 64 which are pivotally held to the transversely extending rod 36 and said arms 64 are connected by an integral transversely extending bar 65. This bar 65 carries a tappet for actuating the dog carrier and also is adapted to operate the parts of the ribbon mechanism. The transverse bar 65 has a rearwardly extending portion 66 which has a hooked end 67. This end 67 is adapted to engage over a transversely extending rod 68 which con- 120 125 130

nects the two supporting arms 28 together, the purpose of the rod and hooked portion 67 being to limit the forward rocking movement of the rocking frame 63, the latter being restored to its normal position by means of a spring, not shown, or otherwise.

It will be evident that by providing the universal bar frame which is connected to 10 the levers 59 arranged on opposite sides of the machine, which are themselves connected together by a transversely extending rod, a uniform movement during the action of the universal bar is imparted to the rocking 15 frame 63. It will be further evident that the parts when in the normal position or that shown in Fig. 1, have both pivots of the link 58 and the pivot rod 41 for the universal bar frame in substantially a 20 straight line and a toggle-joint connection is made between the levers 59 and universal bar. If one of the key-levers 17 is depressed, the said lever will have a movement until the tongue 43 engages the trans- 25 versely extending universal bar 42 of the universal-bar frame without actuating said bar. If the rest of the movement of the key be divided into substantially four equal parts owing to the position of the pivots 30 of the link and the universal bar, the first quarter will give little or no movement to the levers 59. During the next quarter movement of the key a very little additional movement is given to the levers 59, while 35 about one-half of the entire movement of said lever is given during the third quarter of the movement of the key-lever. The final quarter movement of the key-lever after it begins to actuate the universal bar will 40 give substantially the final half throw to the levers 59 and similar movements will thereby be imparted to the rocker frame 63. The rocker frame and the levers 59 will thus be given an accelerated movement in 45 such a way that the universal bar gradually takes up the resistance offered by the parts operated thereby and by reason of the light construction of the universal bar substantially no resistance is offered to the move- 50 ment of the key-levers so that there is no shock and consequently less noise is made by the impact of the key-lever against said universal bar. It will be evident further that the parts when constructed as shown 55 may be readily made and assembled and that the whole universal bar frame can be easily assembled in the machine by simply spreading the offset ears 41^a of the fulcrum plates 14 and 15 slightly apart which allows the 60 outer end of the transverse rod 41 carried by the arms 40 of the universal bar frame 39 to enter the openings in the offset ears 42. The parts, therefore, as herein de- 65 scribed discloses an effective universal bar action and while only one way of carrying

the invention into effect is shown herein, it will be understood that some of the parts may be changed or others substituted therefor without departing from the spirit of the invention.

Having thus described my invention, I claim as new and desire to secure by Letters Patent:—

1. In a typewriting machine, the combination of a rocking frame, means operated thereby, a transversely extending rod, levers connected to said transversely extending rod adapted to move the rocking frame, links connected to said levers, a pivotally held universal bar frame having parts to which the links are connected, the pivot of the universal bar frame and the points of connection of the links with said universal bar frame and the levers being normally in substantially a straight line, springs normally forcing the universal bar frame in one direction, spacing means adapted to limit the downward pivotal movement of the universal bar frame, and key-levers having the engaging portion thereof located under and normally at a distance from the universal bar frame and adapted during the depression thereof to elevate said frame and impart an accelerated movement to said levers.

2. In a typewriting machine, the combination of a rocking frame adapted to operate other mechanism, levers operatively connected to move the rocking frame, links connected to said levers, a pivotally held universal bar having parts to which the links are connected, the pivot of the universal bar and the points of connection of the links with said universal bar and the levers being normally in substantially a straight line, means normally forcing the universal bar in one direction, spacing means adapted to limit the downward movement of the universal bar, and key-operated levers having the engaging portion thereof located under and normally at a distance from the universal bar and adapted during the depression thereof to elevate the universal bar and impart an accelerated movement to said levers.

3. In a typewriting machine, the combination of a rocking element, vertically arranged and pivotally held levers connected to move the rocking element, links connected to said levers, a pivotally held and horizontally arranged universal bar frame having parts to which the links are connected, the pivot of the universal bar frame and the points of connection of the links with said universal bar frame and the levers being normally in substantially a straight line, and key-operated levers having the engaging portion thereof located under and adapted during the depression thereof to elevate the universal bar frame and impart an acceler- 130

ated movement to said levers and rocking element.

4. In a typewriting machine, the combination of levers, means operated by said levers, links connected to said levers, a horizontally arranged and pivotally held universal bar having parts to which the links are connected, the pivot of the universal bar and the points of connection of the links 10 with said universal bar and the levers being normally in substantially a straight line, spacing means adapted to limit the downward movement of the universal bar, and key-operated levers adapted during the depression thereof to elevate the universal bar and impart an accelerated movement to said levers.

5. In a typewriting machine, the combination of a rocking frame, levers operatively connected to move the rocking frame, links connected to said levers, a horizontally arranged and pivotally held universal bar frame having parts to which the links are connected, spacing means adapted to limit 25 the downward movement of the universal bar frame, and key-levers having the engaging portion thereof located under the universal bar frame and adapted during the depression thereof to elevate a part of said 30 frame.

6. In a typewriting machine, the combination of a universal bar, key-operated levers for moving said bar, and an actuating element operatively connected to the universal bar and having an accelerated movement in a general direction opposite to the movement of said bar.

7. In a typewriting machine, the combination of a universal bar, key-operated levers 40 for operating said bar, a pivotally held actuating element, and a substantially toggle-joint connection between the universal bar and said element adapted to impart an accelerated movement to the element.

45 8. In a typewriting machine, the combination of a universal bar, key-operated levers for operating said bar, an actuated element, and connections between the universal bar and the actuated element comprising a plurality of pivotally connected parts so connected that the actuated element is given an accelerated movement in a general direction opposite to the movement of said bar.

55 9. In a typewriting machine, the combination of a universal bar, key-operated levers for operating said bar, an actuated element, and substantially toggle-joint connections between the universal bar and the actuated element for imparting an accelerated movement to said element.

10. In typewriting machines, the combination of a pivotally held universal bar, key-operated levers for operating said bar, an 60 actuated element, and connections including

substantially a toggle-joint between the universal bar and the actuated element, said connections being normally in a straight line and adapted to impart an accelerated movement to said element in a direction opposite to the movement of said bar. 70

11. In a typewriting machine, the combination of a pivotally held universal bar, key-operated levers directly engaging and moving said bar, an actuated element, and connections between the universal bar and the actuated element comprising a link-and-lever connection pivotally held together and having their pivots in substantially a straight line with the pivot of the universal bar and imparting an accelerated movement 80 to said actuated element.

12. In a typewriting machine, the combination of a pivotally held universal bar, key-operating levers for moving said bar, an 85 actuated element, and a pivotally held link-and-lever connection between the universal bar and said element having their pivots in substantially a straight line with the pivot of the universal bar and imparting an accelerated movement 90 to said actuated element in a direction away from said bar.

13. In a typewriting machine, the combination of a rocking element, key-levers, a horizontally arranged and pivotally held 95 universal bar located above and directly operated by said key-levers, and connections including a toggle-joint between the universal bar and the element whereby an accelerated movement is imparted to said element. 100

14. In a typewriting machine, the combination of a universal bar, key-levers located under and adapted to move said universal bar, means for limiting the movement of the 105 universal bar in one direction, a rod, and means including a toggle-joint operatively connected to the universal bar and to the rod to adapt said rod to remain substantially inactive during the initial movement 110 of said bar and then gradually becoming active and increasing its speed during the remaining continued movement of said bar.

15. In a typewriting machine, the combination of pivotally held means, key-levers, a pivotally held universal bar, and connections including toggle-joints between the universal bar and pivotally held means for imparting an accelerated movement to said means. 115

16. In a typewriting machine, the combination of key-levers, a universal bar supported over said key-levers and at a distance above the same when in a normal position, pivotally held levers, means operated 125 by said levers, and links and forming a toggle-joint connection between the levers and the universal bar in such a way as to have an accelerated movement imparted to said levers. 130

17. In a typewriting machine, the combination of key-levers, a pivotally held universal bar supported over said key-levers and at a distance above the same when in a normal position, vertically arranged and pivotally held levers, means operated by said levers, and links connecting the levers to the universal bar and having such connections in substantially a straight line with the pivot of said universal bar.

18. In a typewriting machine, the combination of key-levers, a horizontally arranged and pivoted universal bar supported over said key-levers and above the same when in a normal position, vertically arranged and pivotally held levers, means operated by said levers, and substantially horizontally arranged links connecting the levers to the universal bar above and at the rear thereof.

19. In a typewriting machine, the combination of a rocking frame, pivotally held levers adapted to move said frame, a pivoted universal bar, key-levers adapted to operate said universal bar, parts projecting upward from said universal bar, and links connecting such parts of the universal bar to the levers at points in substantially a straight line with the pivots of the universal bar.

20. In a typewriting machine, the combination of a rocking frame, pivotally held levers adapted to move said frame, a universal bar frame, key-levers located under and normally at a distance from said frame and adapted to operate said universal bar frame, parts projecting upward from said universal bar frame, and horizontally arranged and rearwardly extending links connecting such parts of the universal bar to the levers at points in substantially a straight line with the pivots of the universal bar for the purpose set forth.

21. In a typewriting machine, the combination of a rocking element, a pivotally held lever adapted to move said element, a universal bar, key-levers adapted to operate said universal bar, and a link connecting the universal bar to the lever at points in substantially a straight line with the pivots of the universal bar.

22. In a typewriting machine in which the type-bars have an upward and rearward movement, the combination of a pivotally held rocking frame, pivotally held levers, a rod connecting one end of the levers and extending transversely of the machine and adapted to rock said frame, a universal bar frame substantially U-shaped in form, a rod to which the universal bar frame is held so as to have an up-and-down pivotal movement, key-levers having engaging portions underlying said universal bar frame and normally at a distance therefrom, springs normally forcing the universal bar toward

the key-levers, and links connecting the levers and universal bar frame and having their connections with said levers and universal bar in substantially a straight line with the pivot of said bar.

23. In a typewriting machine in which the type-bars have an upward and rearward movement, the combination of a pivotally held rocking frame, pivotally held levers connected to rock said frame, a horizontally arranged universal bar frame substantially U-shaped in form, a rod to which the universal bar frame is held so as to have an up-and-down pivotal movement, key-levers having engaging portions underlying said universal bar frame and adapted to engage the same, means normally forcing the universal bar frame toward the key-levers, means for limiting the downward movement of said bar, and links connecting the levers and universal bar.

24. In a typewriting machine in which the type-bars have an upward and rearward movement, the combination of a pivotally held rocking frame, pivotally held levers, a rod connecting one end of the levers extending transversely of the machine and adapted to rock said frame, a universal bar frame substantially U-shaped in form, a rod to which the universal bar frame is held so as to have an up-and-down pivotal movement, key-levers having engaging portions underlying said universal bar frame and adapted to operate the same, means normally forcing the universal bar frame toward the key-levers, and links connecting the levers and universal bar.

25. In a typewriting machine in which the type-bars have an upward and rearward movement, the combination of a pivotally held rocking frame, pivotally held levers connected to rock said frame, a pivotally held universal bar frame substantially U-shaped in form, key-levers having engaging portions underlying said universal bar frame and normally at a distance therefrom, springs normally forcing the universal bar frame toward the key-levers, and rearwardly extending links connecting the levers and universal bar frame.

26. In a typewriting machine, the combination of key-levers, a pivotally held universal bar; a rocking element, a space lever for limiting the movement of the universal bar in one direction, and connections between the universal bar and the rocking element to move the same in opposite directions and give the latter an accelerated movement.

27. In a typewriting machine, the combination of a support, a transversely extending rod, a rocking element, a part projecting from said rocking element and adapted to engage said rod to limit the movement of said element in one direction, escapement

mechanism operated by the rocking element, and means for operating said rocking element.

28. In a typewriting machine, the combination of a support, a transversely extending rod, a movable element, escapement mechanism adapted to be operated by said element, a part projecting from said element and having means to engage said rod to limit its movement in one direction, and a universal bar and means connected thereto for giving an accelerated movement to said element.

29. In a typewriting machine, the combination of a support, a carriage adapted to move along said support, a rocking element, key-operated levers, a pivotally held universal bar, and fulcrum supporting plates to which the universal bar is detachably held.

30. In a typewriting machine, the combination of a supporting frame, a carriage adapted to move along said frame, a movable element, key-operated levers, a pivotally held universal bar, and fulcrum supporting plates to which the universal bar is detachably held.

31. In a typewriting machine, the combination of fulcrum supporting plates, a machine frame to which the plates are held, rods extending transversely of the machine between the plates, key-levers suspended from said rods in sets, downwardly and forwardly extending portions forming a part of said plates, a bar held in said portions, springs connected to said bar and to the key-levers, a universal bar pivotally held between said fulcrum supporting plates, springs connected to parts of said plates and to the universal bar, a rocking element, and means connecting said universal bar to said rocking element.

32. In a typewriting machine, the combination of fulcrum supporting plates, a machine frame to which the plates are held, rods extending transversely of the machine between the plates, key-levers suspended

from said rods in sets, downwardly and forwardly extending portions forming a part of said plates, said portions having slots in their forward ends, a bar held in the slots of said ends, a universal bar pivotally held between said fulcrum supporting plates, a rocking element, and means connecting said universal bar to said rocking element.

33. In a typewriting machine, the combination of fulcrum supporting plates, rods extending transversely of the machine between the plates, key-levers suspended from said rods in sets, downwardly and forwardly extending portions forming a part of said plates, a bar held in said portions, springs connected to said bar and to the key-levers, a universal bar pivotally held between said fulcrum supporting plates, and means operated by the universal bar.

34. In a typewriting machine, the combination of fulcrum supporting plates, key-levers supported between said plates, downwardly and forwardly extending portions forming a part of said plates, a bar held in said portions, springs connected to said bar and to the key-levers, a universal bar pivotally held between said fulcrum supporting plates, and means operated by said bar.

35. In a typewriting machine, the combination of fulcrum supporting plates, key-levers supported between said plates, downwardly and forwardly extending portions forming a part of said plates, a bar held in said portions, springs connected to said bar and to the key-levers, a universal bar pivotally held between said fulcrum supporting plates, springs connected to parts of said plates and to the universal bar, and means operated by said universal bar.

This specification signed and witnessed this tenth day of March, A. D. 1915.

OTTO PETERMANN.
